Term of patent 3½ years

To all whom it may concern:

Be it known that I, Mattie Gross, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The dominant feature of my design resides in the adjustable sleeves, tying with a piping.

The parallel lines extending around the neckline represent a contrasting collar.

The dress is opened beneath the buttons along the front.

I claim:

The ornamental design for a dress, substantially as shown and described.
